PROCESS AND APPARATUS FOR PREPARING WEBS FROM FIBROUS MATERIALS

Application filed July 30, 1929, Serial No. 382,240, and in Sweden April 17, 1928.

This invention relates to a process and apparatus for absorption or extraction of liquid from fibrous material, and more especially to a process and apparatus for the production 5 of webs of material from pulp-, cellulose- or peat-fibres, or any similar material, deposited in water or in any other liquid, without the material being damaged, either through hard mechanical pressing between cylinders, 10 or by drying at a higher temperature than the material is able to endure.

The process consists in removing water from, or drying such a mixture of material by being subjected at one side to a higher 15 pressure than that at its other side when passing through a closed chamber, onto a drum of which a portion thereof is perforated in order to allow the removing of the liquid or moisture and drying air or gas, 20 if such fluid is used, which on account of the higher pressure is pressed through and out of the mixture of material.

In the handling of a mixture of material, either of two different ways may be used. 25 By one way, the mixture fills entirely the closed chamber, which is subjected to a high pressure either by pumping the mixture of material directly under high pressure into the chamber, or by introducing the mixture 30 of material into the closed chamber from a hopper situated at a suitably adapted height, the other side of the mixture or path of material at the same time being freely exposed to the free air.

35 By the other way, the mixture of material only partly fills the closed chamber, which in this case is subjected to a higher pressure by means of a pressure fluid, consisting of cold or heated air, or gas or a gas mixture, 40 which is introduced into the closed chamber by means of a steam injector, compressor or similar device, and with the high pressure adapted to the conditions, so that the pressure fluid on account of this high pressure 45 penetrates between, or makes its way past, the fibres in such a mixture of material into the free air, thus carrying with it liquid or moisture until desired dryness of substance 50 contents is reached.

With a continuous path of material or a

mixture of material of a solid consistence, only the last mentioned way with a pressure fluid can be used.

Apparatus of various construction for taking-up, removing the water from, and drying materials deposited in a liquid, such as paper, cellulose, wood-pulp and the like, are old and well known, and these might be said to be divided into two main sections, a wet section and a dry section, which sections, separately, may be constructed in different ways.

The wet section may, for instance, be constructed with plane-endless wire-cloth combined with felt-presses or corrugated rotatable high-pressure presses, or rotating suction 55 sieves, constructed with similar felt-presses or corrugated presses, or any other taking-up member, where the removing of water takes place by means of mechanical pressing, or vacuum, or both of them, while the drying 60 section may, for instance, be constructed with variable sized cylinders heated by steam about which the path of material is carried during the rotation of the cylinders, and the gradual drying of the material effected by 65 heat in the transmission of steam through the cylinders in the path of the material.

The treatment of material in the above described wet section, especially if corrugated, feltless presses are used, is of such a 70 nature that, if the fibres of the material are not directly damaged, the path of material is so hard pressed together, that the work for the disintegration of the path of material necessary at the paper mills rendered more 75 difficult and made more expensive. In addition it is a fact, that the fibres in the layers of the path of material lying farthest off are damaged through the relatively high temperature in the steam cylinders. 80

Heretofore attempts have been made to avoid this last-mentioned disadvantage by a construction of drying section, at which the path of material is dried by direct contact with warm air, which thus obtains an opportunity of sweeping either over a continuously fed path of material, or over the material to be dried, the latter having first in a special way been comminuted in flakes, or fibres, which are intimately mixed with the drying 85

air by agitators constructed for this purpose.

Even if the fibres by this method of drying avoid being damaged, there remains, however, the already mentioned disadvantage from the wet section, namely, that the work of the disintegration of the path of material is rendered more difficult and made more expensive.

The apparatus for carrying out the process described above may mainly consist of a pressure box, having in its bottom a rotatable drum with a perforated mantle, and in which pressure box a mixture or path of material passing through the same is subjected to a high pressure as has been stated under the process described above.

In the accompanying drawings:

Figure 1 is a vertical sectional elevation of one form of apparatus for carrying out the process in accordance with the invention.

Figure 2 is a similar view of another form of apparatus.

Figure 3 is a similar view of another form of apparatus.

Figure 4 is a similar view of another form of apparatus.

Figures 5, 6, and 7 are vertical sectional elevations of still further forms of construction of apparatuses.

Referring to the drawings, particularly Fig. 1 there is shown a pressure box or receptacle 1, the bottom of which is arranged a perforated, rotatable drum 2 provided either with or without special filtering-cloth about its mantle. The mixture of material is introduced into the pressure box 1 through the pipe 3 from a hopper 4 located at a suitable elevation, the pressure box being thus always filled with a mixture of material under a pressure higher than the pressure at the inside of the drum. A layer forming a path of material 5 is formed on the upper side of the rotating drum 2 at some point of its circumference, where necessary packing is arranged, this being effected in any well known manner, so that the path of material is brought to pass between the rotating drum 2 and a rotating taking-off cylinder 6. The packing of the latter against the wall of the pressure box 50 is also effected in any desirable manner, for instance by an elastic element 7, which on account of the pressure in the box is pressed against the cylinder 6 and tightens against the same.

55 Packing between the front sides of the pressure box, on the one hand, and between the rotatable drum 2 and the taking-off cylinder, on the other hand, is also carried out in the usual well known manner. The drying of the contents or the path of material may be regulated at will within certain limits by raising or lowering the pressure in the pressure box, or by regulating the concentration of the introduced mixture of material, or by both 60 expedients.

The liquid pressed out of the material is allowed to pass into the free air through the drum 2, or is gathered in the drum and led away in the usual or well known manner.

The apparatus shown in Fig. 2 of the drawings consists also of a pressure box 1, the bottom of which is provided with a rotatable drum 2. The path of material 5 is taken off from the cylinder 6, and the packings are effected by an elastic element 7, identically as in Fig. 1.

The mixture of material is pressed in through the pipe 3 by means of a force-pump or an elevated hopper 4. At the same time a pressure fluid, for instance air, of a high or low temperature, or gas or a gas mixture is pressed in through the pipe 8. The level "a" of the mixture of material in the pressure box 1 is determined by regulation of the supply through the two pipes 3 and 8. The layer of material which constantly is formed on the drum 2 follows the rotating drum above the level "a" of the mixture of material, and the removing of water and the drying respectively is effected thereby, that the pressure fluid, on account of the higher pressure in the pressure box relatively to that at the inside of the drum, flows through the layer simultaneously carrying away particles of liquid. The path of material finally leaves the drum 2 in any desirable manner. By proportioning the size of the apparatus and regulating the rotation of the drum, the concentration of the mixture of material, and the temperature, and the pressure and temperature of the pressure fluid, any desired dryness of substance contents of the material to be treated is reached.

With certain qualities of mixtures of material more difficult to be treated, it has appeared to be advantageous to precisionize the passage of the pressure fluid through the mixture or path of material with the aid of an endless felt or wire-cloth 10 placed on rolls 9 in the pressure box 1, which wire-cloth by means of a driving device on any of the rolls, in a known way, obtains a suitable peripheral speed in proportion to the outer circumference of the path of material.

For economical reasons, it has appeared to be advantageous to apportion the removing-of-the-water and drying, in certain cases, to two or more pressure boxes, each of the same construction and mode of operation as heretofore described. The only difference is, that the path of material 5, in such a case, is introduced into the pressure box with the aid of a roll 11 as shown in Fig. 3.

The embodiment according to Fig. 4 involves two or more rotatable drums 2, these being surrounded by a common mantle, which forms the closed chamber. This chamber is separated into different compartments by means of dividing walls 12, to enable the introduction of pressure fluid with varying 130

pressures and varying temperatures respectively into these different compartments.

If desired, the high pressure in the pressure box may also be regulated relatively to the pressure at the other side of the mixture or path of material by combining the rotatable drum of some, or of all of the described embodiments with another pressure box arranged in such a way, that the lower side of the mixture or path of material is subjected to a pressure not coming up to, or exceeding the atmospheric pressure, but which, under all circumstances, is lower than the pressure at the upper side of the mixture of material.

Even other embodiments are possible, where the closed chamber is obtained in a way as shown for instance in Figs. 5, 6 and 7.

Further, the invention may of course in those cases, where suitable, be combined with rotating presses with or without felt, or for instance with drying sections used to increase the dry substance contents, or the temperature, or both these things, or the path of material by pressing and heating respectively.

This invention may, of course, with regard to the process as well as to the apparatus, easily be so applied, that a continuous path effected by the treatment in the closed chamber leaves said chamber either in the form of a continuously running path, or in the form of an intermittently fed path (the path is in both cases continuous) thereby, that the rotating drum in Figs. 1, 2 and 3 of the drawings or corresponding parts of other embodiments, are arranged for continuous or intermittent rotation.

Having now described our invention, what we claim as new and desire to secure by Letters Patent is:

1. In an apparatus for separating fibrous material from a liquid holding the material in suspension, the combination of a pressure chamber; a rotatable perforated drum forming a depositing bed in the pressure chamber for the material; and means for introducing said suspension into the chamber and for feeding it in contact with the bed under a substantial static head above atmospheric pressure, thereby producing a continuous compact path of material on the drum.

2. In an apparatus for separating fibrous material from a liquid holding the material in suspension, the combination of a pressure chamber; a rotatable perforated drum forming a depositing bed in the pressure chamber for the material; means for introducing said suspension into the chamber and for feeding it in contact with the bed under a substantial static head above atmospheric pressure, thereby producing a continuous compact path of material on the drum; and means for supplying gaseous fluid under such pressure to the pressure chamber that a part of the drum surface is above the liquid level in the chamber.

3. In an apparatus for separating fibrous

material from a liquid holding it in suspension, the combination of a pressure box; a rotatable perforated drum forming a depositing bed in the pressure box for the material; means for introducing said suspension into the box and for feeding it in contact with the bed under a substantial static head above atmospheric pressure, thereby producing a continuous compact path of material; means for supplying gaseous fluid under such pressure to the box that a part of the drum surface is above the liquid level in the box; an endless perforated band in the pressure box, contacting with the material on the bed in the gaseous fluid space; and means for driving said band.

4. In an apparatus for separating fibrous material from a liquid holding it in suspension, the combination of a pressure box; a rotatable perforated drum forming a depositing bed in the pressure box for the material; means for introducing said suspension into the box and for feeding it in contact with the bed under a substantial static head above atmospheric pressure, thereby producing a continuous compact path of material; means for supplying gaseous fluid under such pressure to the box that a part of the drum surface is above the liquid level in the box; an endless perforated band in the pressure box, contacting with the material on the bed in the gaseous fluid space; means for driving said band; and a take-off cylinder for the layer of material on the bed, said cylinder being mounted in the opening in the box wall through which the path of material is taken from the drum, and being tightened against said box wall by means of packing elements.

5. The herein-described process consisting in separating fibrous material from liquid, holding it in suspension by introducing the suspension into a pressure chamber, and feeding it in contact with a permeable bed in said chamber under a substantial static head above the atmospheric pressure.

6. The herein-described process in which the fibrous material, separated from the liquid which has held it in suspension, forms a layer on a rotatable perforated drum and is subjected to the action of a gaseous fluid under a pressure above the atmospheric pressure for removing water from the layer.

7. In an apparatus for separating fibrous material from a liquid holding the material in suspension, the combination of a pressure chamber; a rotatable perforated drum forming a depositing bed in the pressure chamber for the material; means for introducing said suspension into the chamber and for feeding it in contact with the bed under a substantial static head above atmospheric pressure, thereby producing a continuous compact path of material on the drum; a separate closed chamber, the bottom of which comprises part of the surface of a rotating per-

forated drum; means such as feed- and take-off cylinders for feeding into and out of this second chamber the layer of material already consolidated in the first chamber; and means for supplying gaseous fluid under pressure to the second chamber.

8. In an apparatus for separating fibrous material from a liquid holding the material in suspension, the combination of a pressure chamber; a rotatable perforated drum forming a depositing bed in the pressure chamber for the material, means for introducing said suspension into the chamber and for feeding it in contact with the bed under a substantial static head above atmospheric pressure, thereby producing a continuous compact path of material on the drum; a separate closed chamber; means such as feed- and take-off cylinders for feeding into and out of this second chamber the layer of material already consolidated in the first chamber; and means for supplying gaseous fluid under pressure to the second chamber, the bottom of the second chamber comprising a part of the surface of a plurality of rotatable perforated drums.

9. In an apparatus for separating fibrous material from a liquid holding the material in suspension, the combination of a pressure chamber; a rotatable perforated drum forming a depositing bed in the pressure chamber for the material; means for introducing said suspension into the chamber and for feeding it in contact with the bed under a substantial static head above atmospheric pressure, thereby producing a continuous compact path of material on the drum; a separate closed chamber; means such as feed- and take-off cylinders for feeding into and out of this second chamber the layer of material already consolidated in the first chamber; and means for supplying gaseous fluid under pressure to the second chamber, said second chamber being subdivided into two or more compartments by dividing walls.

10. In an apparatus for separating fibrous material from a liquid holding the material in suspension, the combination of a pressure chamber; a rotatable perforated drum forming a depositing bed in the pressure chamber for the material; means for introducing said suspension into the chamber and for feeding it in contact with the bed under a substantial static head above atmospheric pressure, thereby producing a continuous compact path of material on the drum; and means for varying the pressure inside the drum so as to adjust the difference of pressure through the layer of material.

11. In witness whereof, we have hereunto signed our names.

EINAR FRITIOF SUNDSTRÖM.
